CALENDAR CLOCK

Laurens Hammond, Evanston, Ill., assignor to
 The Hammond Clock Company, Chicago, Ill., a
 corporation of Delaware

Application September 12, 1931, Serial No. 562,459

3 Claims. (CL. 58—6)

My invention relates generally to calendar clocks, and more particularly to improvements in the operating mechanism for the day and date indicating mechanisms of such clocks.

5 It is an object of my invention to provide a simplified mechanism for operating day of the week and date indicating means in conjunction with an electric clock.

10 A further object is to provide a calendar clock which has a small number of operating parts, in which the operation is certain, in which most of the parts are stampings, and which may be economically manufactured.

15 A further object is to provide an improved calendar clock in which the day of the week and date indicating means may readily be reset.

20 A further object is to provide an improved calendar clock having two indicators, one for the units and one for the tens indication of the date of the month, and to provide common means for actuating said units and tens indicators without the necessity of employing a transfer mechanism.

25 Other objects will appear from the following description, reference being had to the accompanying drawings, in which

Figure 1 is a perspective view of the complete clock;

Figure 2 is a vertical sectional view of the 30 clock casing with the hands and dial removed;

Figure 3 is a sectional view taken on the line 3—3 of Fig. 2;

Figure 4 is a sectional view taken on the line 4—4 of Fig. 2;

35 Figure 5 is a bottom plan view of the clock;

Figure 6 is a sectional detail showing the actuating means for the date indicating wheels;

Figure 7 is a view similar to Fig. 2 with the front dial supporting plate broken away to show 40 the parts located beneath it;

Figure 8 is a side elevation showing the detent means for holding the indicating wheels; and

Figure 9 is a fragmentary sectional view taken 45 on the line 9—9 of Fig. 2.

The clock comprises a molded case 10, which may be molded of a suitable phenol condensation product, having four soft rubber feet 12 which fit into recesses in the base of the casing. The mechanism of the clock is supported by a 50 pair of spaced frame plates 14, 16, to which are attached a back-cover plate 18 and a front plate 20. The latter is covered by a dial 22, which is secured to the front plate 20 by having corner lugs 24 (Fig. 8) thereof bent around the plate 20, 55 the lugs fitting into notches 26 (Fig. 2) cut in the

corners of the plate 20. A sheet 27 of glass is held between the peripheral edge flange of the dial 22 and a bezel flange 28 formed around the front of the case 10. The entire clock works are held in the case by screws 30. The plate 20 has a plurality of depressed portions 32 struck therefrom, these portions being fastened to the plate 16 by means of nuts and bolts 34.

The clock mechanism may be of any suitable construction, but is preferably synchronous motor 10 driven. A satisfactory mechanism of this type is disclosed in my copending application Serial No. 390,551, filed September 5, 1929, now Patent No. 1,924,853, dated August 29, 1933.

As best shown in Fig. 7, the hour hands of the 15 clock are driven from a pinion 36 which meshes with the gear 38 secured to the hour-hand sleeve 40. The gear 38 has a pinion 42 rigidly secured thereto, the latter meshing with a gear 44. As illustrated in Fig. 2, the shaft 45 upon which the 20 gear 44 is fixed has secured thereto a disc 47, which is positioned within a depression formed in the front plate 20. The halves of the disc 47 are colored in contrasting colors and a small portion of this disc is visible through a small aperture 25 49 formed in the dial plate 22.

A pin 46 secured to the gear 44 projects outwardly therefrom so as to lie within an irregularly shaped opening 48 formed within the enlarged portion 50 of a lever 52. The lever 52 is pivoted 30 at 54 and has its free extremity pivotally connected to a vertically slid able bar 56 by a stud 53. This bar is guided by a pair of shouldered rivets 58, which are secured to the front plate 20. A pair of pawls 60 and 62, which are preferably 35 integral and punched from a sheet of spring steel, are riveted to the lower end of the bar 56.

A pair of brackets 64, 66, struck from the plate 20, form bearings for a shaft 68. The shaft has an annular groove adjacent each end thereof to 40 receive a retaining spring clip 70.

The shaft 68 serves as the pivotal support for three wheels or drums 72, 74 and 76, which form indicators for the days of the week, and the tens and the units of the days of the month, 45 respectively. The drum 72 comprises a drawn shell 78 (Fig. 4), one end of which is closed by a dished head 80, having a notched outwardly extending rim 82 for engagement with a spring detent 84, which is riveted to the plate 20 at 50 85. A ratchet wheel 86 is riveted to the other end of the shell 78, said ratchet having seven equally spaced teeth. The tens drum 74 is cup-shaped, having its end wall secured to a sleeve 88, to which is secured a ratchet wheel 90. The 55

drum 74 has a flanged rim 89 with ten notches therein for engagement with a detent 91 (Fig. 2). The units drum 76 is likewise cup-shaped, having its end wall 92 secured to a sleeve 94, which is 5 rotatably mounted on a shaft 68. The rim 93 of the drum 76 has ten notches therein for cooperation with detent 95. The sleeve 94 carries a ratchet wheel 96 which lies closely adjacent the ratchet wheel 90; the two ratchet wheels being 10 held apart, and hence the drums 74 and 76 held close together by a spider spring 98.

The ratchet wheels 90 and 96 each have ten teeth but the root diameter of the ratchet wheel 96 is greater than the outside diameter of the 15 ratchet wheel 90, there being, however, a single notch in the ratchet wheel 96, which is approximately twice as deep as the remaining notches on this wheel, for a purpose which will be described hereinafter.

20 A certain amount of frictional drag is imposed upon the drum 76 by a coil spring 100 which is wound about a guide sleeve 102 which is shoudered to form a seat for one end of the spring, the other end of the spring engaging the end 25 wall 92 of the drum 76.

A stop member 104 has one end passing through a suitable opening in the front plate 20 and has an apertured lug 106 riveted thereto. This lug fits between the two ratchet wheels 86 30 and 96, the member having a pair of sidewardly extending projections 108 which limit inward movement (to the left, Fig. 3) of the ends of the spring pawls 62 when the latter are in their uppermost position.

35 The base of the case 10 is provided with apertures 110, 112 and 114, which are sufficiently large to permit the manual rotation of the drums 72, 74 and 76 to set the latter. The drum 72 is suitably marked with the days of the week, the 40 drum 74 with duplicate sets of numerals "1", "2", "3" and the word "Set", while the drum 76 is marked with the numerals "0" to "9", inclusive.

The operation of the clock is as follows: The pinion 42 rotates with the gear 38 at a speed 45 of one revolution in twelve hours. The gear 44 has twice as many teeth as the pinion 42 and hence will make one revolution in twenty-four hours. The gear 44 rotates in the direction of the arrow shown in Fig. 7 and through engagement of its pin 46 with the edges of the opening 48 swings the lever 52 upwardly about its pivot 54, thereby raising the slide-bar 56. This operation takes place relatively slowly. After the gear 44 has rotated approximately 180° counterclockwise from the position in which it is shown in Fig. 7, it will cause a rapid downward movement of the bar 56, this movement taking place during angular displacement of less than 30° on the gear 44 due to the shape of the opening 48. 55 Downward movement of the bar 56 to its lowermost position is assured by the engagement of the pin 46 with the lower edge of the opening 48.

60 During this downward movement of the slide-bar 56, the pawls 60 and 62 will engage the teeth of the ratchet wheels 86 and 96, thereby rotating the latter and the drums to which they are connected. The ratchet wheel 86 will, due to the spacing teeth, be rotated through one-seventh of a revolution, whereas the ratchet wheel 96 will be rotated through one-tenth of a revolution. Although both pawls 60 and 62 have the same length stroke, the stroke is just sufficient 65 for the pawl 62 to travel a distance equal to or 70 slightly greater than that between the teeth 75

of the ratchet wheel 86 but not sufficient to travel twice the length of the spaces between the teeth of the ratchet wheel 96. Thus at the beginning of a downward stroke, the pawl 62 will first engage a tooth of the ratchet wheel 86 and move the latter a short distance and, thereafter, the pawl 60 will engage a tooth of the ratchet wheel 96. After the pawl 60 thus operatively engages the ratchet wheel 96, the pawl will continue its downward movement and rotate the ratchet wheel 86 through an angle of 36°, at the same time completing the rotation of ratchet wheel 96 through one-seventh of a revolution. Rotation of the drums is limited and overthrow prevented through engagement of detents 84, 91 and 15 95 in the notches of the flanges 82, 89 and 93, respectively.

When the units drum is in a position to indicate the digit "9", the deep notch in the ratchet wheel 96 will lie beneath the pawl 60 and the latter will thereby move inwardly toward the shaft 68 sufficient to engage one of the teeth of the ratchet wheel 90. The ratchet wheels 90, 96, and hence their drums 74, 76, will be moved together one-tenth of a revolution so as to register 25 "10". This mechanism thus performs the functions of a transfer or carry-over mechanism. The indicia upon the various drums are visible through openings 118 and 120 formed in the dial plate 22, as best shown in Fig. 1.

30 The calendar date indicating mechanism operates automatically for only one month, it being necessary manually to reset the date indicating drums at the end of each month. If this resetting is neglected for ten days the word "Set" 35 will appear on the tens drum through the sight opening 120.

In view of the fact that it is necessary that the calendar indications change during the night, the clock must be set not only to the correct 40 hour and minute, but also with reference to whether the time is A. M. or P. M. This can be ascertained by noting the color of the portion of the disc appearing through the aperture 49.

45 It will be noted that the operating mechanism for the day and date indicators is positive, that is, the bar 56 is positively moved in both directions, thus being substantially noiseless. Because of the relative slowness of the movement of the bar 56, it is unnecessary to provide elaborate 50 overthrow mechanism, and the remaining parts may likewise be made more simple and lighter in weight. The fact that the rims 82, 89 and 93 are located so as to be manually engageable for setting also greatly simplifies the construction.

55 While I have illustrated and described a preferred embodiment of my invention, many modifications may be made without departing from the spirit of the invention, and I do not wish to be limited to the precise details set forth but 60 desire to avail myself of all changes within the scope of the appended claims.

1. In a clock, the combination of a clock mechanism having a pinion rotatable once in twelve hours, a gear driven by said pinion, a pivotally mounted lever, interengaging means on said lever and gear for causing oscillation of said lever upon rotation of said gear, a slidably mounted bar pivoted to the free end of said lever, a plurality of indicating members, and means associated with 65 said bar and said members to cause diverse degrees of angular movement of said members upon reciprocation of said bar by said lever.

70 2. A day and date indicating means for clocks comprising a plurality of indicating drums hav- 75

ing the days of the week, the tens of the date and the units of the date respectively marked thereon, each of said drums having a ratchet wheel fixed thereto, all of said ratchet wheels being located side by side adjacent one another, the ratchet wheel fixed to said day indicating drum having seven equally spaced teeth, the ratchet wheel fixed to said date units indicating drum having ten equally spaced teeth, and a deep notch formed between two of the teeth thereof, the ratchet wheel fixed to said tens date indicating drum being of smaller diameter than the ratchet wheel fixed to the units date indicating drum and having a plurality of spaced teeth; a shaft common to all of said drums and forming a support therefor, pawl means engageable with said ratchet wheels to rotate said drums, said pawl means including a common pawl engageable with the ratchet wheels fixed to said units and tens date indicating drums but held from engagement with the former except when the deep notch of the ratchet wheel of said units date

indicating drum is in position to be engaged thereby, whereby said tens date indicating drum will be operated one space each time said units date indicating drum is rotated through a complete revolution.

3. In a clock, the combination of a clock mechanism, a member reciprocated once in twenty-four hours by said mechanism, three rotatable drum-shaped indicators each having a ratchet wheel associated therewith, a shaft common to 10 said indicators for supporting them for rotation, said ratchet wheels having different numbers of spaced teeth thereon and being located immediately adjacent one another, resilient pawls secured to said reciprocating member and engageable with said ratchet wheels to rotate the latter diverse angular distances upon reciprocatory movement thereof, manually engageable rims on said indicators, and detent means cooperable with said rims for holding said indicators in position. 15 20

LAURENS HAMMOND.
